UNITED STATES PATENT OFFICE.

FRANZ GRAF, OF BADEN, SWITZERLAND.

ELECTRICALLY-HEATED TILE STOVE.

Application filed June 26, 1924, Serial No. 722,611, and in Switzerland July 3, 1923.

This invention has for its object to provide an improved electrically heated tile stove wherein the electrical heating elements are located in the cavity of the several tile units. This arrangement has great advantages.

A constructional form of an improved stove according to this invention is illustrated by way of example in the accompanying drawings in which:—

Figure 1 is a vertical longitudinal section, and

Figure 2 is a cross-section thereof.

The improved stove is composed of three layers each of four pot-shaped tiles *a*, the middle layer consisting of three tiles and a hot cupboard *b*. The tiles of the two lower rows are provided with a heat-storing filling *c* of sand that covers completely the heating resistance *d* which is located in the interior of each tile. Above the heating resistance *e* of the upper layer of tiles there is located for the purpose of serving as a heat storage device, a block of steatite *f* with sufficient play *g* to allow the heated air to flow past it directly into the apartment to be heated. The hot cupboard *b* is made of iron.

The tiles are placed upon one another without cement, and they may be held together in the several horizontal layers by clamps *h* which are fastened in the passage holes *i*. In the absence of cement jointing, this method of assembly, owing to the irregularity of the tile surface, ensures interstices between contiguous tiles for the circulation of air. The improved stove is covered with an iron cover plate *k* and stands on an iron foot or bed plate *m* in the interior of which the main electrical terminals *n* are located in a very accessible but also well protected manner.

At the top there is arranged a damper *q* which may be composed of a fixed plate and a movable plate, both of heat-storing material, for instance a mixture of asbestos and cement known as "eternite," so that the damper itself serves as a heat-storing device. By means of this damper the warm air can be retained in the interior of the stove, more particularly in the interstices between the several pots according to requirement, or it may be delivered as a continuous current into the apartment to be heated.

Collector bars *p* lead to the electrical connections of the heating elements *d* and *e* in

the several tiles through a passage *c* formed by shallow grooves in the sides of the tiles from the main terminals *n*. For the purpose of making different electrical connections more than two collector bars 60 will naturally be required. The connections of the resistances *d* and *e* is effected by way of the apertures *i*. By suitable known electrical switching devices, single parts of the stove may be arranged to be thrown into and 65 out of operation separately.

Owing to the improved stove being built up of single heating cells the said stove is not only very readily transportable, but also it can be divided up into units each capable 70 of independent heating. Even each single tile-pot may be used by itself for heating an apartment or an article. The improved stove can also be sub-divided into two, three or more part-stoves each of which is composed of a group of tiles so that with a single stove one apartment can be heated to a high temperature for instance in cold weather, and a plurality of apartments can be heated to a lower temperature when the 75 weather is warmer. On the other hand by building up further tile-pots the output of the improved stove can be increased afterwards on the spot to any desired extent.

Owing to the fact that each single tile 80 can be provided with a heating element the structure of the improved stove is not limited to the usual conventional forms.

For example the tiles may be placed in a single layer or even in a single row upon 85 one another or side by side. In this manner the floor may be laid with these tiles, or a wall may be covered with them. If the wall is replaced by a wall composed of heating tiles, this arrangement allows of heating two 90 rooms at one and the same time. Furthermore, the apartment, or single pieces of furniture, may be bordered with a row of tiles, or the tiles may be placed on a cornice or on 95 a bracket. Pillars and columns may also be built up of the tiles which may serve for instance as a casing for T-iron supports. Finally, the tiles may be placed upon one 100 another in the form of steps or benches, or other fancy shapes may be formed there- 105 with.

In many of the above mentioned cases care must be taken that the temperature of the tiles does not exceed a determined maximum. The heating according to the de- 110

scribed system can be effected quite readily by employing a large number of slightly heated tiles instead of a few highly heated tiles.

- 5 Often it will not be necessary to make all the tiles heated, and in such a case therefore the heating elements may be omitted from some tiles. The various tiles may be made more or less capable of retaining heat 10 by filling only a portion of the tiles with a storage-material, for instance sand, enclosing the heating element, and filling the other tiles only partly, or not at all, as shown at the top in the drawing; so that a current of 15 hot air is caused to flow through the heating element, and the apartment to be heated more quickly. By omitting the filling material from all the tiles, the improved stove may be converted into a direct-heating stove 20 with less storage capacity, an effect which can be increased by leaving the front wall of all or some of the tiles open, or by covering the open front wall with sheet metal. By substituting metal pots for ceramic tile pots, 25 it is possible to obtain a rapid heating of the apartment and greater radiation of heat.

Since every tile has its own heating resistance, it is an easy matter to regulate the heat of the improved stove. For instance, 30 the tiles may be cut-out of operation singly or in groups, or be changed over, or be connected in series and in parallel, and the connection may be changed from star-connection to delta-connection in the case of three- 35 phase current.

What I claim is:—

1. An electrical heating stove comprising a plurality of interchangeable rectangular cup-shaped units, each of said units containing a heating element and being filled with 40 granular material, and a plurality of connecting means on the sides of each of said units coacting with corresponding connecting means on adjacent units.

2. An electrical heating stove as claimed 45 in claim 1; wherein any one of said heating elements may be electrically disconnected from the others of said heating elements.

3. An electrical heating stove as claimed in claim 1, wherein the hollow units are 50 formed with apertures for the passage of electric connecting leads.

4. An electrical heating stove as claimed in claim 1, wherein all the units are formed with vertical grooves which coact to form a 55 vertical passage for the reception of electrical supply leads.

5. An electrical heating stove as claimed in claim 1, wherein all the units are formed with vertical grooves which coact to form a 60 vertical passage for the reception of electrical supply leads, said electrical supply leads being united to form collector bars.

6. An electrical heating stove as claimed in claim 1, wherein the uppermost layer of 65 hollow units is covered by a plate of heat-storing material.

In testimony whereof I have signed my name to this specification.

FRANZ GRAF.
